(Cl. D54—14)

To all whom it may concern:

Be it known that I, Bernhard A. Runstrom, a citizen of the United States, residing at Madison, in the county of Dane and State of Wisconsin, have invented a new, original, and ornamental Design for a Motor Driven Hand Tool Unit, of which the following is a specification, reference being had to the accompanying drawing, forming part thereof.

In the drawing:

Figure 1 is a side elevation of the motor driven hand tool unit.

Figure 2 is an end elevation thereof.

The dominant features of my design reside in the portions shown in full lines.

I claim:

The ornamental design for a motor driven hand tool unit, as shown and described:

BERNHARD A. RUNSTROM.
